UNITED STATES PATENT OFFICE.

OSCAR W. CROPLEY, OF JUNIATA, NEBRASKA.

GRAIN-SEPARATOR.

1,273,462.

Specification of Letters Patent.

Patented July 23, 1918.

Application filed November 16, 1914. Serial No. 872,448.

To all whom it may concern:

Be it known that I, OSCAR W. CROPLEY, a citizen of the United States, residing at Juniata, in the county of Adams and State 5 of Nebraska, have invented certain new and useful Improvements in Grain-Separators, of which the following is a specification.

This invention relates to the class of rotary sifters and has particular reference to 10 a device for use in connection with grain or similar material as a chaff separator.

As a principal object, this invention contemplates the provision of a grain sifter of the type described which shall be simple of 15 construction, compact in form and capable of separating grain from its attendant particles of foreign or useless matter in an efficient manner.

The above and additional objects which 20 will become apparent as this explanatory description proceeds are accomplished by such means as are illustrated in the accompanying drawings, described in the following specification and then more particularly 25 pointed out in the claims which are appended hereto and form a part of this application.

With reference to the drawings, wherein 30 there is illustrated the preferred embodiment of this invention as it is reduced to practice, and throughout the several views of which like characters of reference designate similar parts:

Figure 1 is a perspective view of one of 35 the grain sifting machines comprehended by this invention,

Fig. 2 is a side elevation of the machine shown in Fig. 1, substantially, but equipped with a varied form of separator.

40 Fig. 3 is an end view of the matter shown in Fig. 2,

Figure 4, is a detail in plan of driving connections shown in Fig. 3,

Fig. 5 is a detail sectional view taken 45 longitudinally through the body of the separator showing the guide boards arranged for use with the double sieve of Fig. 2 and in dotted lines the arrangement of said boards for the single sieve in Fig. 1.

50 There is illustrated a machine including a pair of parallel side boards 10 formed at the front with suitable handles 11 and being cut away as at 12 in order to be suitably secured to the upper portion 13 of a fan cas-

55 ing designated as a whole by the numeral 14. Suitable handles 15 are also secured to

the side boards 10 at the rear end thereof so that the machine may be readily carried about. When stationary the grain sifter is supported by a pair of short forward legs 60 16 suitably braced as at 17 and by a second pair of rearward legs 18, which extend upwardly beyond the side boards 10 in order to receive bearings 19 for a countershaft 20, upon the center of which shaft is mounted 65 a beveled gear 21 and upon one extremity a large sprocket wheel 22, which is provided with a handle 23 for manual rotation thereof, although it will be obvious that the sprocket may be connected with any suitable 70 source of motive power if desired.

Within the fan casing 14 is mounted a fan including blades 24 secured to a central shaft 25 on the extremity of which is carried a small sprocket 26 adapted to be 75 driven by customary chain connections 27 from the large sprocket 22. A U-shaped support 28 has its extensions fastened to the respective side boards 10 toward the rear of the machine and supports as illustrated 80 a hopper 29 which may be of any desirable size and shape and is provided at the bottom with a suitable outlet to which is connected a delivery spout 30 which is adapted to convey the grain to be sifted to the rotary sifting devices. 85

One of these sifters is illustrated in Fig. 1 and includes principally a foraminous cylinder 31 braced at the ends by bands 32 and mounted for revolution with the shaft 90 33 by means of the usual hubs and spokes which in the latter instance may be formed from wire. This sifter is positioned longitudinally of the machine intermediate of the base boards 10 and is mounted at its 95 forward extremity in a bearing 34 mounted on an arm 35 which may be adjusted for height by a pin and series of apertures in connection with a transverse board brace 36. At its rearward end the sifter 31 is 100 maintained in driving relation with the operating means of the machine by a bracket 37, V-shaped as illustrated more particularly in Fig. 4, so that the end of the shaft 33 which carries a beveled gear 38 105 may make suitable connections with the gear 21 carried centrally of the shaft 20. By this means it will be seen that driving the large sprocket 22 accomplishes movement of all the necessary parts of this sifter. 110

Between the side boards 10 there is slidably positioned in guides 39 a guide plate

40 for the sifted grain, such plate being positioned immediately below the sieve 31 at an angle to conduct the grain to the distributing aperture 41. A similar set of 5 guides 39', see Figs. 2 and 5, oppositely slanted, are also mounted on the side boards 10 to receive the guide plate 40 when two concentric sieves 46 and 47 are employed for directing the grain from the outer sieve to a 10 distributing aperture 48. The guide plate slides easily in guides 39 and 39' and may be readily shifted from one set to another as circumstances require. In the forward portion of the space between the side boards 15 there are positioned upon the bottom 42, a pair of oppositely inclined chaff guides 43 illustrated in Fig. 5 and serving a purpose to be more fully described hereinafter. A gate 44 is mounted above and at an angle 20 to the chaff guide 43 for obvious sliding movement between a pair of guides 45 secured upon the side boards 10. Any suitable control means may be employed for the adjustment of this gate 44 since movement 25 of this gate determines the quantity of material to be blown away from the sifted grain.

In Fig. 2 is illustrated another form of such machines as are comprehended by this 30 invention and in which the main difference will be seen to be in the rotary sifter itself, which in this instance comprises an outer foraminous cylinder 46 and a similar but smaller inner cylinder 47, the former being 35 of a finer mesh than the latter and both being mounted for rotation upon the shaft 33 in some manner similar to that already described in the case of the sifter 31. It should be particularly noted however that 40 the inner cylinder 47 extends forwardly beyond the forward limit of the outer cylinder for a purpose to be later more fully set forth. If desired the shaft 33 may be inclined upwardly toward the rear in order 45 to facilitate the passage of the grain through the sieves.

In operation, the hopper 29 is first filled with the grain to be separated which is permitted to flow through the spout 30 to 50 the interior of the sifter 31, in the first instance, such flow being controlled by any desirable shiftable means suitably interposed in the mouth of the delivery spout. Operation of the sprocket 22 either by hand or other motive power effects the rotation of the sieve 31 as well as of the fan which latter generates the blast of air used as the final step in the separating operation. The rotary sieve 31 operates upon the admitted grain in the 55 usual manner, sifting out the larger particles of foreign matter and depositing the cleaned grain upon the guide board 40 which is in the position illustrated in Fig. 1 and in dotted lines Fig. 5 and by which 60 the grain is rapidly conducted to the dis-

charge aperture 41 formed in the bottom 42. Just before passing through this aperture however the grain is subjected to the fan blast issuing from the portion 13 of the casing and serving to blow away the lighter 70 particles of chaff which have already been loosened in the travel of the grain through the machine. The heavier portions of the grain mass which are of course that part it is desired to retain may be gathered below the discharge 41 by any suitable receptacle since the fan blast is not sufficiently strong to blow these portions away. The sliding gate 44 as will be obvious upon reference to Fig. 5, may be raised by the operator to a suitable height to permit the chaff to be blown thereunder over the inclined surface of the chaff guide 43.

The operation of the separator illustrated in Fig. 2 differs but slightly from that 85 already described. When using the double sieve the guide board 40 is withdrawn from the guides 39 and inserted in the guides 39' so as to occupy the inclined position shown in Fig. 5 with its lower end terminating between the distributing aperture 41 and the similar aperture 48 in rear thereof, and its upper end immediately below the foremost end of the outer cylinder 46 so that the projecting portion of the inner cylinder 47 will 90 extend beyond said board and be immediately above the sliding gate 45. It will thus be apparent that all grain fine enough to pass through the inner cylinder, but too coarse to pass through the outer cylinder 100 will be deposited in a stream on the gate 45 separate from that grain passing through both inner and outer cylinders. From gate 45 grain thereon will flow to the delivery aperture 41 while the coarser grain collected 105 by the board 40 will gravitate to the aperture 48. Any grain falling on the top of the fan casing may be, from time to time, pushed forward so as to fall through aperture 48 or it may be removed from the rear 110 of the machine.

While in the foregoing however, there has thus been illustrated in the drawings and described in the specification such combination and arrangement of elements as constitute the preferred embodiment of this invention, it is desired to emphasize the fact that such minor changes in the matters of proportion and degree may be made in later adaptations of this device, as shall not alter 115 the spirit of the invention as defined in the appended claims.

What is claimed is:

1. A grain separator including a hopper, a sieve below the hopper, and a fan below the sieve, in combination with suitable means for directing the flow of grain from said sieve across an air blast from said fan, deflecting means in rear of the path of flowing grain to carry away chaff separated by 130

said air blasts, and slidably adjustable means controlling the amount of chaff reaching said deflecting means.

2. A grain separator including a hopper, 5 a sieve below the hopper, and a fan below the sieve, in combination with a shiftable and adjustable guide board to receive the sifted grain from said sieve and conduct it to a suitable discharge aperture, said fan 10 adapted to force an air blast across the path of the flowing grain as it falls from the guide board to separate the chaff therefrom, and means for deflecting said chaff from the finally discharged grain.
- 15 3. The combination in a grain separator including a hopper, a pair of concentric sieves below the hopper and a fan below the sieves, of a pair of guide boards to receive separately the grain from said sieves and 20 deliver the same across the blast of air from said fan to separate discharge apertures, and means in rear of the path of the flowing grain for deflecting the chaff separated from said grain and effecting suitable discharge 25 of the same.

4. A grain separator including a hopper, a sieve below said hopper, grain conducting means between said hopper and said sieve, a reversible guide board beneath said sieve 30 and capable of angular adjustment with relation thereto for suitably conducting the sifted grain to the discharge aperture, a fan operable with said sieve and adapted to generate an air blast for acting upon said 35 grain across its direction of flow and immediately above its discharge to separate the chaff therefrom loosened by said sieve, and means in front of said guide board for deflecting said chaff to a point of discharge.
- 40 5. The combination in a grain separator, of a hopper, a pair of concentric revolving sieves, an adjustable guide board beneath said sieves to receive grain passing through the inner sieve and conducting the same to 45 a suitable discharge aperture, an angularly slidable and reversible guide board for re-

ceiving grain passing through the outer sieve and conducting the same to a second discharge aperture, a fan adapted to drive a blast of air across the flow of both streams 50 of grain immediately before entering the discharge apertures to separate therefrom chaff loosened by said sieves, and means for deflecting said chaff to a point of discharge remote from said apertures. 55

6. A grain separator including a hopper and a sieve, of supporting side boards, a bottom connecting said side boards and having a grain discharge opening formed therein, an inclined adjustable member 60 mounted upon said side boards below the sieve and terminating at its lower end adjacent said discharge opening, a removable and reversible grain conducting board for operating in one position with said inclined 65 adjustable member for conducting the grain to said discharge opening, means for directing an air current across the stream of grain falling from said adjustable member to the discharge opening, and chaff directing means 70 mounted upon the bottom in front of the adjustable member.

7. In a grain separator, a receiving chute therefor of trough-like shape having discharge openings in the bottom thereof for 75 the passage of grain, and an inlet opening for a current of air across the bottom of said chute and parallel thereto, deflector boards removably mounted in said chute and adjustable to vary the distance between 80 the lower edges thereof and the bottom of the chute for regulating the passage of air thereunder, and its action on the descending grain, and a chaff deflector at the end of the chute opposite the air inlet opening. 85

In testimony whereof I affix my signature in presence of two witnesses.
